UNITED STATES PATENT OFFICE.

JOHN H. HAWLEY, OF NEW YORK, N. Y.

DESIGN FOR A BUTTON.

46,125.

Specification for Design.

Patented July 21, 1914.

Application filed June 1, 1914. Serial No. 842,318. Term of patent 3½ years.

To all whom it may concern:

Be it known that I, JOHN H. HAWLEY, a citizen of the United States, and a resident of the borough of Manhattan, city and State of New York, have invented a new, original, and ornamental Design for Buttons, of which the following is a specification.

My design is represented in the accompanying drawing in which:

Figure 1 is a plan view. Fig. 2 is a side view. Fig. 3 is a section one line 3—3 of Fig. 2 of the button illustrating my new design.

The design consists of the ornamental shape shown.

As shown the general contour of the button is conical. The base of the cone, however, which in my button forms the top sur-

face thereof is convex. The intersection of the top or convex base with the side of the cone is a curved surface. The eye of the button is formed in the apex of the cone. The entire surface of the button is of a uniform color.

I claim:

The ornamental design for a button as shown and described, or any colorable imitation thereof.

In testimony that I claim the foregoing as my own, I have hereto affixed my signature in the presence of two witnesses.

JOHN H. HAWLEY.

Witnesses:

ISABEL R. RICHARDS,
C. C. BILLINGS.
